United States Patent Office

Des. 221,775
Patented Sept. 7, 1971

221,775

COMBINED RADIO AND CASSETTE TAPE RECORDER OR SIMILAR ARTICLE

John S. Maliskas, North Syracuse, N.Y., assignor to
General Electric Company

Filed June 5, 1970, Ser. No. 23,336

Term of patent 14 years

Int. Cl. D14—01

U.S. Cl. D26—14

FIG.1

FIG.2

FIG.3

FIG. 1 is a front elevation view of a combined radio and cassette tape recorder or similar article;

FIG. 2 is a side elevational view, the antenna being omitted for convenience in illustration; and

FIG. 3 is a top plan view.

I claim:

The ornamental design for a combined radio and cassette tape recorder or similar article, as shown.
